(57) CLAIM

The ornamental design for a bottle, as shown and described.

DESCRIPTION

FIG. 1 is a top, front, right side perspective view of a bottle showing my new design;

FIG. 2 is a front side elevational view thereof, the rear elevational view being identical;

FIG. 3 is a right side elevational view thereof, the left side elevational view being identical; and,

FIG. 4 is a top plan view thereof.

Please note that the rear and the left side views have been omitted since they are identical respectively to the front and to the right side views.
